UNITED STATES PATENT OFFICE.

JOHN A. MCCOY, OF FALL RIVER, MASSACHUSETTS.

TELEPHONE SWITCH-BOARD.

SPECIFICATION forming part of Letters Patent No. 251,123, dated December 20, 1881.

Application filed September 14, 1881. (No model.)

To all whom it may concern:

Be it known that I, JOHN A. MCCOY, of Fall River, county of Bristol, and State of Massachusetts, have invented a new and useful Improvement 5 in Telephone Switch-Boards, of which the following description, in connection with the accompanying drawings, is a specification.

My invention relates to telephone switch-boards, and has for its object to facilitate the 10 operation of connecting and disconnecting the subscribers' circuits.

In large exchanges several hundreds and perhaps thousands of different subscribers' circuits enter a single central office passing through 15 a switch-board, the object of which is to enable any desired pair of the said circuits to be connected into one continuous circuit for the intercommunication of subscribers thereon. In the most common arrangement the subscribers' circuit-wires entering the central office are 20 arranged side by side, and numbered in regular order to distinguish them, and each passes through a signal or indicating instrument by which the central office is signaled. Suitable 25 connecting-strips are arranged each in proper proximity to all the different subscribers' wires to be readily connected therewith, such a strip, when connected with any two of the circuits—as by a plug, key, or flexible connector—continuing 30 the circuit from one to the other. A separate connecting-strip must be employed for each pair of circuits that are connected at a given time. In an exchange containing a large 35 number of circuits that are frequently used a large number of operators are required, and in the most common plan of operation a certain number of subscribers' wires are assigned to the care of each operator. For example, if there are five hundred subscribers' circuits, 40 numbered from 1 to 500, respectively, there may be ten operators or sets of operators, numbered from 1 to 10, and each having charge of fifty wires. If a subscriber on one of the first fifty wires desires to communicate with 45 another subscriber, he signals the central office, and operator number 1 there receives the signal and places himself in communication with the said subscriber to find out what is desired. If the subscriber wishes to communicate 50 with another subscriber on one of the first fifty circuits, the said operator can himself make

the proper connection; but if he desires to communicate with a subscriber on any other circuit—as, for example, the 140th—the said operator No. 1, in charge of the first fifty wires, 55 will have by some means to communicate with operator No. 3, in charge of wires 101 to 150, inclusive, to find out first whether wire No. 140 is already in use or not, and, if not, the said operators No. 1 and No. 3 will have to connect the two subscribers' circuits with a common connecting-strip not in use by any other pair of subscribers. When the communication is ended both operators will have to disconnect the respective subscribers' circuits from 60 the connecting-strip.

This invention consists in a combination and arrangement of devices whereby each central operator can discover whether any of the subscribers' circuits not under his especial supervision is or is not in use, or by which he can 65 connect any circuit under his supervision with any other circuit entering the office.

Figure 1 illustrates in diagram a portion of a central-office apparatus of a telephone-exchange system embodying my invention; Fig. 2, a vertical section of the indicating-instrument for a subscribers' circuit and the other devices connected therewith; Fig. 3, a detail showing some of the parts shown in Fig. 2, but 70 in a different position; and Fig. 4, a modification to be referred to.

In the following description the same letters of reference will be used for the corresponding parts in the different sections of the apparatus 75 under the charge of the different operators; and index-marks will be used with said letters corresponding to the number of the operators' sections to which they belong—as, for example, a' indicates the subscribers' wires in charge of operator No. 1, a'' those in charge of No. 2, and so on; and when a device is spoken of without regard to the different sections the index-marks will be omitted, the letter a thus indicating the subscribers' circuits in general. 80 A sufficient number of circuits are shown in full to illustrate the connections and the operations of the parts, the rest being omitted to 85 avoid confusion.

A' A'' represent the different sections of the 90 apparatus in charge of operators No. 1 and No. 2, respectively, they containing the terminals of

- the subscribers' circuit-strips a' a^2 , &c., numbered in order and connected in the usual manner with a switch-board, the sections B' B^2 , &c., of which may be of any usual construction.
- 5 The connecting-strips b' b^2 of the said sections are independent of one another, each being in proximity only to the subscribers' circuits of the same section therewith. The said subscribers' strips a are connected in circuit, as by wires
- 10 e , with the indicating-instruments d , which may operate annunciator-drops in the usual manner, their magnets having wound upon them two independent coils, from one of which, connected with the subscribers' strips a , the circuit is continued by wire e to a spring, f , normally forced by an insulating-plug, g , as shown in Fig. 2, against a metallic ground-strip, h , common to the springs f of all the said subscribers' circuits a of the same section A'
- 15 A^2 , &c., and connected with the ground, so that a subscriber, by sending an electric impulse over his circuit, will operate the indicating-instrument d for that circuit in the usual manner.
- Corresponding to each of the springs f is a
- 20 25 spring, i , forced by the plug g , inserted between it and the said spring f , against a metallic battery-strip, j , connected by wire k through a battery, l , to the ground. The said springs i' of the first section are connected by
- 30 wires m' with the other coil of the indicators d' , from which the circuit is continued by the wire n' to the tables D^2 D^3 , &c., of the apparatus in charge of all the operators—No. 2, No. 3, &c.—other than the one in whose section the said
- 35 indicating-instrument belongs.
- The table, D' , in charge of operator No. 1 contains different rows or series of terminal plates, o^2 o^3 , &c., connected in a similar manner with the wires n^2 from the indicators d^2
- 40 45 of the apparatus, A^2 , in charge of the second operator, and by wires n^3 with the indicators in charge of the third operator, and so on. The table, D' , in charge of the first operator thus contains the open terminals of wires passing from a battery through a coil of each indicating-instrument of the portions of the apparatus in charge of the other operators besides himself. The plates o in the different tables D bear the same numbers as the indicating-in
- 50 struments d connected with them, and the indicating-instruments of each section can be operated from every other section, as follows:
- Each operator is provided with a signaling-instrument, p , which may be an ordinary telegraph-sounder or a tap-bell having one electrode connected, as by wire r , to the ground, and the other electrode terminating in a normally-open plate or strip, s . The springs f i are adapted to make contact with one another and
- 55 60 become disconnected from the bars h j when the insulating-plugs g are withdrawn, as shown in Fig. 3; and it will be seen that when a plug, g , is thus withdrawn the circuit from the corresponding subscriber's line a is continued, by
- 65 wire e , one coil of the instrument d , wire e , springs f and i , wire m , the other coil of the same instrument d , and wire n , to the open

terminal plate o in each of the other tables D of the apparatus.

It will be seen that in this arrangement each subscriber's circuit in one section of the apparatus has an extension-circuit passing to each other section of the apparatus, the said extension being, in the arrangement illustrated in Figs. 1 to 4, normally disconnected from the main circuit by the plug g , but adapted to be connected continuously therewith by the withdrawal of the said plug, so that the said circuit is brought within the control of the operators at all parts of the apparatus. The operator at any table, by connecting the terminal plates o passing to the corresponding indicating-instrument d in any other part of the switch-board with his sounder-plate s , will, if the plug g corresponding to the said indicating-instrument is inserted, complete the circuit from the battery-strip j through the outer coil of the said indicating-instrument and his sounder or signaling-instrument p , thus operating the said indicating-instrument and his signaling-instrument. If the said sounder does not respond, the operator will know that the battery's circuit just described is not complete, the plug g being removed, and that the subscriber's circuit corresponding to the said spring is in use. If, however, the sounder does respond and the indicating-instrument is affected, the operator in whose section it is will know whether the said indicator was affected by another operator or by a subscriber from the difference in character of the currents employed, the subscriber using magneto-currents, which are momentary in their action on the armatures of the indicating-instruments, and the central-office operators using the battery, with which they can hold the armatures for definite intervals, or "write dashes," by properly making and breaking the connection with the sounder-plate. When an operator sees his indicating-instrument affected by another operator, he removes the corresponding plug g , thus continuing the desired subscribers' circuits, as above described, to the table D of the said other operator, who can signal over and connect it with the desired subscriber's circuit in his portion of the switch-board B in any usual manner.

In the form shown in Fig. 1 the terminal plates o are provided with plug-sockets, to enable them to be connected by a flexible cord with the sounder-plate s , or with the subscribers' circuits a or connecting-bars b of the switch-board; and in the form shown in Fig. 4 the connecting-strips b of the switch-board are connected with strips upon the table D in proximity to the terminal plates o , so that by inserting a plug or stem connection in the socket shown between the said terminal plate and strips the terminal plate will be connected with one of the connecting-strips b ; and the latter are provided with normally-open keys t , to enable them, when connected with one of the terminal plates o , to complete the circuit to the said sounder-plate. The tables D thus form what may be termed "auxiliary switch-boards,"

since they, in connection with the main switch-board *b*, enable each operator to connect the circuits under his charge with any other circuits of the exchange.

5 The operation is as follows: Suppose that subscriber No. 51 desires to communicate with subscriber No. 1, the said subscriber No. 51, by an electric impulse applied in any usual manner, operates the indicating-instrument *d*² as a signal to operator No. 2, who places himself in communication with circuit No. 51 in any usual manner, and learns therethrough that a connection is desired with circuit No. 1. He accordingly connects *p*'*o*', No. 1, of his table *D*² with the sounder-plate *s*², thus closing the circuit from the ground through the sounder *p*² to the plate *o*', and thence by wire *n*' to one coil of the inductor *d*' of circuit No. 1, whence the circuit is completed by wire *m*', spring *v*', strip *j*', through the battery to the ground. This is supposing that the plug *g*' for the said circuit No. 1 is inserted, for if it is not no circuit will be made and the sounder *p*² will not respond to the last-described operation. By thus connecting the plates *o* and *s* when the plug *g* is inserted, the indicating-instrument *d*' of circuit No. 1 will be affected, and the operator No. 1 thus signaled will remove the plug *g* without further attention, thus connecting subscriber's circuit No. 1, as hereinbefore described, with the terminal plate *o*' in the table *D*², so that the operator No. 2 will merely have to connect the said terminal plate *o*' with the subscriber's line No. 51 to place the two subscribers in communication, as desired.

In the section *B*' of the switch-board the subscribers' strips *a*' are shown as provided with plugs *u*, by which the connection through the indicator *d* with the ground may be cut off when the said subscribers' lines are connected by the operator for that section with others.

It is obvious that two indicators *d* might be used for each circuit, if desired, one being included in the main portion of the subscriber's circuit—as between the wires *c* and *e*—and operated only by the subscriber, and the other being in the circuit-extension—as between the wires *m* and *n*—and operated only by the central-office attendants; but as there is no difficulty in distinguishing the signals, it is preferable, on account of cheapness, to have one core-armature and drop-piece common to both coils, as seen in Fig. 2.

I claim—

55 1. In a telephone-exchange system, the circuit-connecting apparatus divided into sections, to be in charge of different attendants, each section consisting of a switch-board containing portions of a certain definite number of subscribers' circuits and means to connect them, in combination with an auxiliary switch-board containing portions of extensions from all the subscribers' circuits of the exchange except

the said definite number belonging to that section in question, whereby the operator in charge 65 of a given section can connect any circuit belonging to the said section with any other circuit of the exchange, substantially as and for the purpose described.

2. In a telephone-exchange system, a circuit-connecting apparatus in sections, each section containing a portion of the subscribers' circuits and indicating-instruments therein, and corresponding extension-circuits leading from each of the said subscribers' circuits 70 through indicating-instruments to all the other sections of the apparatus, in combination with circuit-changing devices, as described, whereby the said subscribers' and extension circuits 75 may be disconnected from one another and independently grounded, or may be connected together and disconnected from the ground, substantially as described.

3. In a telephone-exchange system, a subscriber's circuit and indicating-instrument and 85 circuit closing spring connected therewith, and a ground-strip, combined with an extension-circuit containing a circuit-closing spring and indicating-instrument, and a battery-strip, the said devices being arranged as described, 90 whereby the said springs, when separated, disconnect the subscribers' and extension circuits and are brought in contact with the said ground and battery strips, respectively, and the reverse, substantially as and for the purpose described. 95

4. In a telephone-exchange system, a circuit-connecting apparatus in sections, each section containing a main switch-board for forming connections between the circuits of that 100 section, and an auxiliary switch-board containing extensions from the circuits of all the other sections, each normally grounded through a battery and indicating-instrument, in combination with a signaling-instrument adapted to 105 be connected in circuit with any of the said extensions, substantially as and for the purpose set forth.

5. The subscriber's strip and indicating-instrument having two coils, one connected with 110 the said strip and with a circuit-closing spring, combined with the corresponding circuit-closing spring connected in circuit with the other coil of the said instrument, the ground and battery strips, and device to separate the said 115 springs and force them into electrical contact with the said ground and battery strip, respectively, substantially as and for the purpose set forth.

In testimony whereof I have signed my name 120 to this specification in the presence of two subscribing witnesses.

JOHN A. MCCOY.
